(57) **CLAIM**

The ornamental design for a computer chassis, as shown and described.

DESCRIPTION

FIG. 1 is a perspective view of a computer chassis; FIG. 2 is a front view of the computer chassis of FIG. 1; FIG. 3 is a rear view of the computer chassis of FIG. 1; FIG. 4 is a left view of the computer chassis of FIG. 1; FIG. 5 is a right view of the computer chassis of FIG. 1; FIG. 6 is a top view of the computer chassis of FIG. 1; and, FIG. 7 is a bottom view of the computer chassis of FIG. 1. The broken lines in FIGS. 1-7 depict portions of the computer chassis forming no part of the claimed design. The figures show a symbolic break in the width of the computer chassis. The break lines, as well any portion of the article between the break lines, form no part of the claimed design.
